UNITED STATES PATENT OFFICE

CHARLES S. McCARTHY, OF TOLEDO, OHIO, ASSIGNOR TO THE AMERICAN SWISS COMPANY, OF TOLEDO, OHIO, A CORPORATION OF OHIO

LOCKING MECHANISM FOR LATCHES

Application filed December 19, 1925. Serial No. 76,360.

This invention relates to latches, but more particularly to that type of latches used on automobile doors employing members for retracting the bolt, these members being positioned in such a manner as to be accessible from the outside and inside of the automobile respectively.

Objects of this invention are to produce a locking mechanism for latches of the type commonly used on automobiles which may be operated for locking one of the handles against movement by an axial movement of the other handle, and so constructed that when the other handle is turned a predetermined degree, the locking mechanism is automatically rendered inoperative; and to provide a simple and efficient lock for latches having the new and improved constructional features hereinafter described.

Other objects and advantages will herein-after appear and the invention is shown by way of illustration in the accompanying drawings, in which:

Fig. 1 is a side elevation of a latch mechanism embodying this invention; Fig. 2 is a top plan view of the latch mechanism shown in Fig. 1; Fig. 3 is a sectional view taken on the line 3—3 of Fig. 2; Fig. 4 is a sectional view through the sliding latch retractor showing the mounting of the retractor and the construction of one of the gear sectors; and Fig. 5 is an elevational view showing a portion of the cam means for moving the rocking member out of locking position.

The general construction of the latch mechanism shown on the drawings is similar to that shown and described in my copending application for door latch, Serial Number 6,938, filed February 5th, 1925, so that detail description of this construction is not considered necessary in this instance, and a brief description of the construction, arrangement and operation of this mechanism is deemed sufficient.

On the drawings, the supporting plate 1 having a flange 3 is attached in a suitable manner to the door 4 and supported on the plate 1 in spaced relation therefrom is a somewhat smaller plate 4. Slidably between the plates 1 and 4 is a latch bolt 5, the outer

end of which extends through an opening in the flange 3 to engage a stationary keeper (not shown) as will readily be understood. The latch bolt 5 is formed with teeth 6 on opposite sides thereof and these teeth are engageable by a pair of connected toothed sectors 7 through which the retractor rod 8 extends. It will thus be seen that rotation of the rod 8 in a clockwise direction operates to retract the sliding bolt 5.

Suitable bearing members 9 in the plates 1 and 4 are mounted on the outer side of each sector 7 for supporting the rod 8. A spiral spring 10 suitably mounted between the plates 1 and 4 has one end thereof bearing against the inner end of the latch bolt 5 for normally holding the bolt 5 in its advanced position.

For normally holding the sector 7 out of engagement with the teeth 6 on the latch bolt 5 a coil spring 11 surrounds one end of the retractor bolt 8 and rotates the rod 8 to such a position that the teeth on the sectors 7 are moved away from the teeth 6 on the bolt. For convenience in manipulation, a handle 12 may be connected in any suitable manner to the outer end of the rod.

Additional means are provided for retracting the bolt 5 and such means extend at substantially right angles to the retractor rod 8. For this purpose a rod 13 is provided with a squared end which projects into a socket formed in a cam member 14 which, upon counter clockwise rotation engages a horn 15 fixed to the bolt 5 and thereby retracts the bolt 5 against the tension of the coil spring 10. It is to be understood that a suitable handle may be attached to the outer end of the rod 13. When the rod 13 is manipulated the rod 8 is inoperative so that it will be seen that the retractors operate independently of each other.

An outstanding characteristic of this invention resides in the provision of locking means for preventing the retraction of the latching bolt 5 by one of the retractors. This locking means is so constructed as to be operable by the other retractor and preferably the other retractor is manually actuated to effect the locking, thereafter upon a prede-

terminated movement of this retractor, the lock is automatically released.

It will be obvious that such an arrangement as above described is of cardinal advantage on closed automobiles in which three or four doors are used. By my invention it is merely necessary to employ a key-controlled lock for one of the doors and the other doors can be locked from the inside by manipulating the retractor on the inside of the door so as to lock the outside retractor against movement.

The locking mechanism shown on the drawings comprises a lever 16 which is pivoted at one end to the plate 1 adjacent the retractor shaft 8 and extends across this shaft terminating in the region of the cam member 14 which is formed with a notch 17 to receive the free end of the lever. When the end of the lever 16 is positioned in the notch 17, turning movement of the cam member is prevented in both directions (clockwise movement being prevented by the flange 2).

It will be seen that the lever 16 is formed with a curved portion 18 which partially surrounds the retractor shaft 8 and this portion is provided with an inclined elongate slot 19 into which extends a pin 20 fixed to the shaft 8.

For actuating the lever 16 to locking position, the retractor shaft 8 is formed with a squared end portion 8^a which is slidable in square holes in the toothed sectors 7. Thus, by tapping or lightly hitting the outer end 30 of the retractor shaft 8, this shaft is moved downwardly and the pin 20 engaging the side of the slot 19 moves the locking lever 16 to locking position.

In order to emit a clicking sound for audibly indicating that the lever 16 has been moved to locking position, a groove 21 is formed in the lever 16 intermediate its ends and a spring arm 22 secured at one end to the underside of the plate 4 is adapted frictionally to engage the arm 16 and snap into the groove 21. This arm also functions to hold the arm in locking position and prevents the jarring of the vehicle from accidentally displacing the arm.

The locking arm 16 is automatically moved from locking position when the retractor shaft 8 is turned a predetermined degree. It will be apparent when in use an automobile door may be unlocked from the inside by 55 turning the handle 12 to open the door so that the door having a key-controlled lock is first unlocked and the other doors are unlocked from the inside. For accomplishing this, the slot 19 is inclined upwardly on one side and formed in the edge of the plate 1 is a notch 23 having a cam surface upon which a pin 24 fixed to the retractor shaft 8 bears. The cam surface of the notch 23 is inclined similarly to the slot 19 but at a greater angle.

When the handle 12 is turned in a counter-

clockwise direction the pins 20 and 24 co-operate with the slot 19 and notch 23 respectively, axially to move the retractor shaft 8 outwardly and thereby move the locking lever 16 away from the cam member 14 so that movement of the cam member is permitted.

While I have shown and described a construction which satisfies the objects of the invention hereinbefore mentioned, it is to be understood that the above is given merely by way of illustration and not of limitation, and numerous changes in details of construction and arrangement may be effected without departing from the spirit of the invention, especially as defined in the appended claims.

What I claim as new and desire to secure by Letters Patent, is:

1. A latch mechanism having a sliding latch bolt, a pair of independently operable retractors for said bolt, one of said retractors being axially movable, a pivoted lever for locking one of said retractors against movement, and a member carried by said axially movable retractor and slidably engaging said lever intermediate the ends whereby axial movement of said axially movable retractor moves said lever to locking position.

2. A latch mechanism, having a sliding latch bolt, a pair of independently operable retractors for said bolt, one of said retractors being axially movable, a pivoted lever for locking the other retractor against movement, said lever having a longitudinally elongate inclined slot intermediate the ends thereof, a pin on said axially movable retractor extending into said seat whereby axial movement of said retractor moves said member to locking position and turning movement of said retractor moves said member out of locking position.

3. A latch mechanism having a latch bolt, a retractor for said bolt, a lever pivoted at one end and engageable with said retractor at the other end for locking said retractor against movement, an axially movable and rotatable shaft, and means on the shaft engaging said lever whereby axial movement of said shaft moves said lever to locking position and rotation thereof moves said lever away from locking position.

4. A door latch comprising a spring tensioned bolt, a roll back for said bolt, a rotary and axially movable spindle for retracting said bolt, a dog pivoted at one end and directly engageable with said roll back at the opposite end, and a connection between said spindle and an intermediate part of said dog for moving the latter away from the roll back upon rotary movement of said spindle.

5. A door latch comprising a spring tensioned bolt, a roll back for said bolt, a rotary and axially movable spindle for retracting said bolt, a dog pivoted at one end and directly engageable with said roll back at the

opposite end, and means on said spindle engageable with said dog for camming the latter away from the roll back when the spindle is rotated, said dog being movable to dogging position upon axial movement of said spindle.

In testimony whereof I have hereunto signed my name to this specification.
